DUST COLLECTOR

Karl F. Juengling, Lakewood, Ohio, and Hakon A. Berg, Birmingham, Ala.

Application June 26, 1930. Serial No. 464,075

10 Claims. (Cl. 183—86)

Although our invention is capable of general application for dust-collecting purposes, it particularly relates to apparatus of this nature adapted to remove dust from gas, particularly for cleaning gas from blast furnaces.

It is well known that dust-laden gas is discharged from blast furnaces under considerable pressure and hence travels through dust collectors at a high velocity. These dust collectors usually consist of or are provided with a curved passageway through which the dust-laden gas travels and in which the dust is separated from the gas by centrifugal action. The main purpose of our invention is positively to remove the dust which has been centrifugally separated in the separating casing, from the sphere of agitated separating action, this removal being effected at a plurality of spaced exit ports formed in the wall of the curved passageway, the dust so removed through each port settling in a quiet area into a storage bin.

In the event that our invention is utilized for separating dust from a carrier under circumstances wherein the carrier is not given a high velocity at its source, which, as stated, is true of blast furnace operation, this velocity will be artificially induced by any suitable means, such as feeding the dust-laden carrier through the curved passageway by the action of a blower, or inducing the rapid travel of the dust-laden carrier through the passageway by a suitable suction device.

The annexed drawings and the following description set forth in detail certain means embodying our invention, such means disclosing, however, but two of the various forms in which the principle of the invention may be applied.

In said annexed drawings:

Figure 1 is a central vertical section of our improved dust collector, the view also showing a track and car running thereupon and into which the dust accumulated in the several storage bins may be discharged, the section being taken in the plane indicated by the line 1—1, Figure 2;

Figure 2 is a plan section, taken in the planes indicated by the line 2—2, Figure 1;

Figure 3 is a central vertical section of a modified form of apparatus, taken in the plane indicated by the line 3—3, Figure 4; and

Figure 4 is a planes section, taken in the plane indicated by the line 4—4, Figure 3.

Referring to the annexed drawings in which the same parts are indicated by the same respective numbers in the several views, a dis-

charge pipe 1 (Figures 1 and 2) from a blast furnace (not shown) feeds the dust-laden gas at a high velocity into a casing 2 comprised of a plurality of turns which form a spiral passageway from the outside to the central area of the 60 casing, the pipe 1 discharging tangentially into the casing 2. The dust in the gas under the centrifugal action follows the line of the outer wall of the casing 2 as it traverses the spiral path. By reason of the spiral arrangement, the 65 over-all diameter of each succeeding inner spiral turn is smaller than the adjacently outer one; and furthermore, the cross section of the spiral passageway gradually decreases, as is evident from an inspection of Figure 2. The inner end 70 of the innermost turn of the casing 2 opens at the segmental area 23 into a central chamber 24 which communicates adjacent the top of the casing 2 with an exit passageway 4. Through this latter passageway the cleaned gas passes 75 from the apparatus.

We direct particular attention to the fact that the curved passageway is closed. That is, the pathway of the dust-laden gas from the pipe 1 to the exit 23 is provided in a separate 80 chamber which is of comparatively restricted cross-section, and thus maintains the velocity and centrifugal action. This arrangement is essentially an improvement over those constructions in which the dust-laden gas travels in a 85 comparatively large open chamber and is not caused necessarily to follow a definite restricted pathway. The dust-laden gas in our apparatus does not enter any such comparatively large open chamber until it is discharged through the 90 exit 23 into the central chamber 24. The requirements incident to the operation of blast furnaces of different sizes will govern the particular over-all dimension of the casing 2 and the particular cross-section or gradual decrease 95 in cross-section of the curved passageway in said casing.

The essence of our invention is the provision of means for collecting the dust which is following the outer wall of the various casing 100 turns, into quiet chambers where it may settle into storage bins without further disturbance or agitation. For this purpose we have formed a plurality of spaced vertical ports 5 in the casing wall which open into comparatively narrow vertical chambers 6 which discharge 105 into separate and independent bins 7. This construction is plainly seen in Figure 1. These chambers 6 are closed to any influence which would induce agitation of the dust so that the 110

latter quickly settles into the bins 7. At the bottom of the central chamber 24 we provide a central bin 8. The dust collected in these various bins 7 and 8 can be discharged as desired into a car 9 operating on a track 10 and thus periodically removed from the sphere of operations.

In order that the dust may more positively be directed through the ports 5 into the settling chambers 6, we speed up the travel of the dust-laden gas and hence the centrifugal action adjacently forward of each port 5 by a vane 20 which is secured at its inner end to the casing 2, and extends outwardly any desired amount and is adjustable by a handle 25 or other suitable operating means. This construction creates a restricted passage opening 26 which increases the velocity of the gas travel, as will be readily understood. Furthermore, we provide lips 21 at the far sides of the ports 5 which slightly extend into the gas passageway and serve positively to direct the dust tending to slide across the ports 5, through said ports and into the chambers 6.

In Figures 3 and 4, we show a different form of construction in which a discharge pipe 11 from the blast furnace feeds the dust-laden gas tangentially into a casing 12 comprised of a plurality of turns wound in helical formation and discharging at the bottom into a chamber 13 which communicates adjacent its top with a gas-exit pipe 14. This form of construction also is provided with spaced-casing ports 15 and casing lips 22 adapted to cause the dust which is traveling along the outer wall of the helix under centrifugal action to escape into and settle through the passageways 16 into the bins 17. A bin 18 is also provided at the bottom of the central chamber 13, the bins 17 and 18 being adapted to be emptied into the car 19. This form of construction also is provided with adjustable vanes 27 which are operated by handles 28 and serve to narrow up the cross-section of the passageway, to whatever extent desired, adjacently forward of the ports 15. In the form of construction shown in Figures 3 and 4, the over-all diameter of each turn of the helix is the same as that of each other turn, and the cross-sectional area of the passageway through the casing 12 is the same from its outer end to its inner end, in contradistinction to the varying over-all dimensions and varying cross-sectional areas of the form of device shown in Figures 1 and 2.

Our improved apparatus progressively increases the dust-separating effect as the gases pass from the entrance to the exit of the dust collector; first, by progressively increasing the velocity of the gases through the curved passageway and, secondly, by gradually decreasing the radius of the passageway as the gases pass from the inlet to the outlet of the collector.

What we claim is:

1. In a dust collector, provided with means for inducing the flow of a dust-laden carrier the combination of a curved conduit in which the separation of dust from the carrier is effected by centrifugal action, means comprising a plurality of exit ports and separate speed modifying elements for the carrier cooperating with and located adjacently forwardly of the respective exit ports to provide for the successive removal of separated dust from the outer area of the conduit, separate and independent closed settling chambers communicating respectively with said

last-mentioned means, and means forming an exit from the conduit for the clean carrier.

2. In a dust collector, provided with means for inducing the flow of a dust-laden carrier the combination of a curved conduit in which the separation of dust from the carrier is effected by centrifugal action, means comprising a plurality of exit ports and separate adjustable speed modifying elements for the carrier cooperating with and located adjacently forwardly of the respective exit ports to provide for the successive removal of separated dust from the outer area of the conduit, separate and independent closed settling chambers communicating respectively with said last-mentioned means, and means forming an exit from the conduit for the clean carrier.

3. In a dust collector, provided with means for inducing the flow of a dust-laden carrier the combination of a curved conduit in which the separation of dust from the carrier is effected by centrifugal action, means comprising a plurality of exit ports and a separate speed increasing element for the carrier cooperating with each respective exit port to provide for the successive removal of separated dust from the outer area of the conduit, dust-intercepting lips disposed adjacent the far ends of said exit ports and adapted positively to direct the dust through said ports, separate and independent closed settling chambers communicating respectively with said ports, and means forming an exit from the conduit for the clean carrier.

4. In a dust collector, provided with means for inducing the flow of a dust-laden carrier the combination of a curved conduit in which the separation of dust from the carrier is effected by centrifugal action, means providing for the successive removal of separated dust from the outer area of the conduit, means restricting the cross-section of the conduit adjacent the near ends of said removal means, separate and independent closed settling chambers communicating respectively with said last-mentioned means, and means forming an exit from the conduit for the clean carrier.

5. In dust collector, provided with means for inducing the flow of a dust-laden carrier the combination of a curved conduit in which the separation of dust from the carrier is effected by centrifugal action, means providing for the successive removal of separated dust from the outer area of the conduit, means adjustably restricting the cross-section of the conduit adjacent the near ends of said removal means, separate and independent closed settling chambers communicating respectively with said last-mentioned means, and means forming an exit from the conduit for the clean carrier.

6. In a dust collector provided with means for inducing the flow of dust-laden gas; the combination of means forming a spiral conduit comprised of a plurality of communicating turns whose cross-section constantly decreases to increase the speed of the gas, a plurality of exit ports on the outer wall of said conduit to receive dust separated by centrifugal action from the gas, means adjacently forwardly of the respective exit ports for locally increasing the speed of the gas, means for carrying to a point of discharge separated dust from said exit ports, and means forming an exit from the conduit for purified gas.

7. In a dust collector provided with means for inducing the flow of dust-laden gas; the

- combination of means forming a spiral conduit comprised of a plurality of communicating turns whose cross-section constantly decreases to increase the speed of the gas, a plurality of exit ports on the outer wall of said conduit to receive dust separated by centrifugal action from the gas, the over-all dimension of each succeeding inner turn of the conduit being smaller than the adjacently outer turn to increase the speed of the gas passing therethrough, means on the inner wall of said conduit for locally increasing the speed of the gas in the vicinity of said exit ports, means for carrying separated dust away from said exit ports, and means forming an exit from the conduit for purified gas. 80
- 10 85
- 15 90
- 20 95
- 25 100
- 30 105
- 35 110
- 40 115
- 45 120
- 50 125
- 55 130
- 60 135
- 65 140
- 70 145
- 75 150
- which the separation of the dust from the gas is effected by centrifugal action, the cross-section of the conduit constantly decreasing from end to end, means for successively taking off separated dust from the conduit, means substantially opposite said dust take-off means forming baffles adapted to decrease the effective cross-section of the conduit adjacently forwardly of the several dust take-off means, and means forming an exit from the conduit for purified gas.
10. In a dust collector, provided with means for inducing the flow of dust-laden gas the combination of a casing formed with a conduit of coil formation whose cross-section gradually decreases from its outer end to its inner end and in which conduit the separation of the dust from the gas is effected by centrifugal action, said casing having an entrance opening for dust-laden gas and an upper discharge opening for purified gas, a plurality of dust-discharge openings formed in the respective outer walls of the turns of the conduit, closed settling chambers into which said dust-discharge openings severally feed, a dust bin within said casing and lying below said discharge opening for purified gas and below the exit from said conduit, a plurality of adjustable baffles restricting the effective cross-section of the conduit adjacently forwardly of the several dust-discharge openings, and dust-directing lips disposed adjacent the far ends of the several dust-discharge openings.
